UNITED STATES PATENT OFFICE.

ROBERT C. BROMLEY, OF PITTSBURG, PENNSYLVANIA.

VALVE.

SPECIFICATION forming part of Letters Patent No. 605,384, dated June 7, 1898.

Application filed October 27, 1897. Serial No. 656,573. (No model.)

To all whom it may concern:

Be it known that I, ROBERT C. BROMLEY, a citizen of the United States, residing at Pittsburg, in the county of Allegheny and State of Pennsylvania, have invented or discovered a new and useful Improvement in Valves, of which the following is a full, clear, and exact description, reference being had to the accompanying drawings, forming part of this application, in which—

Figure 1 is a central longitudinal vertical section taken through my improved valve in an opened position. Fig. 2 is a horizontal longitudinal section taken on the line II II of Fig. 1, showing the valve open. Fig. 3 is a similar view showing the valve closed. Fig. 4 is a vertical cross-section taken on the line IV IV of Fig. 1. Fig. 5 is a partial similar view showing the upper disk seated. Fig. 6 is a perspective view of one of the rotating valve-disks. Fig. 7 is a plan view of the center disk-base.

My invention relates to valves, and has particular reference to that class of valves designed for the purpose of seating themselves upon the valve-faces at or about the end of the stroke.

The form of valve embodied in the present invention is designed to avoid and obviate the tendency to bind before the valve is properly in position to close, which is a very general fault with this class of valves and which is entirely overcome in my construction, while I have embodied in it extreme simplicity and cheapness of construction.

Referring now to the drawings, 2 is the valve-case, provided with end flanges 3 for making attachment with the main, or, if desired, threads may be used. The inner faces 4 of the valve-seats are ground to make a flat face which preferably extends backward toward the stem of the valve for a distance approximating the length of travel. Located centrally of the valve-case is a disk-base 5, provided with an extended boss 6, which, with the base, is internally threaded for engagement with the valve-stem 7, mounted in the end of the valve-case and having an encircling collar 8 to prevent longitudinal movement. A gland 9 compresses packing 10 around the stem to prevent leakage. The disk-base 5 is provided on each opposite outer

face with circular inclined planes or cam-faces 11, and upon each of such faces is mounted the disk 12, provided with corresponding cam-faces 13, conforming to the same degree as the faces 11 and with which they conform, so that rotation of the disks upon the disk-base will result in a movement of the disk-faces outwardly or inwardly from 55 or toward the center of the disk-base.

It is desired that the disks shall maintain a non-rotatory position while advancing toward and from the valve-seat, thus preventing friction or wear, and that they will rapidly advance toward and from the seat at the end of the forward stroke and commencement of the back stroke. To this end, each disk is provided with a lateral arm 14, provided with a pivoted roller 15, which in the back travel of 65 the valve bears against the opposite parallel vertical faces 16, reversing the disks upon the cam-faces and allowing them to recede from contact with the faces 4. In the path of each arm 14 at each side is an interfering 70 abutment 17, adapted to engage the forward flat face 18 in the forward travel of the valve and to rotate it in a reverse direction as it advances over the seat 4. The effect of such reverse rotation is to separate the faces of the 75 disks 12 and to cause them to bind tightly against the faces of the valve-seat at the end of the stroke by reason of the expanding action of the contracting cams 11 and 13, and the position and degree of such cams is so adjusted that the disks are brought tightly into contact with the valve-faces just when the valve has reached the proper position of its 80 travel, and further travel is effectually prevented by reason of such binding action. 85 Upon reversal of the valve the pivoted wheels will strike against the corners 19 of the guide 16, throwing the disks around and immediately releasing the pressure by the reverse action of the cams, when the further withdrawal 90 of the valve is rendered comparatively easy.

Upper and lower parallel guiding edges 20 serve to retain the disks in position laterally, their peripheries bearing against such edges 100 at all times, as clearly shown in Fig. 2.

Each disk is provided with a central inwardly-projecting stem or stud 21, which extends into the corresponding opening 22 in the disk-base, such stud serving as an axial

center upon which the disk rotates and whereby it is kept in a central position upon the base. These studs 21 are of comparatively short length and do not extend as far as the 5 threaded hole through the base, so that an uninterrupted passage is left for the stem 7.

Having described my invention, what I claim, and desire to secure by Letters Patent, is—

- 10 1. In a valve, a central reciprocating non-rotary disk-base provided with cam-faces and centrally-mounted rotating valve-disks thereon provided with corresponding cam-faces, substantially as set forth.
- 15 2. In a valve, a central reciprocating non-rotary disk-base provided with cam-faces and centrally-mounted rotating valve-disks thereon provided with corresponding cam-faces and means for rotating the disks, substantially as set forth.
- 20 3. A valve comprising a case having oppositely-located seats, a non-rotary central base adjustably mounted on a valve-stem having inclined faces on opposite sides, and centrally-mounted rotating valve-disks thereon provided with corresponding inclined faces, and means for rotating the disks, substantially as set forth.
- 25 4. A valve comprising a case having oppositely-located seats a non-rotary central base adjustably mounted on a valve-stem having inclined faces on opposite sides, and centrally-mounted rotating valve-disks thereon provided with corresponding inclined faces, and means for rotating and seating the disks on their inward travel and reversing and unseating the disks on their backward travel, substantially as set forth.
- 30 5. A valve comprising a case having oppositely-located seats, guides along the inner sides of the case terminating in abutting ends, abutments beyond such ends, with an inter-

vening recess, and a non-rotary central base adjustably mounted on a valve-stem with rotating valve-disks mounted thereon having 45 projecting arms adapted to engage such abutments and abutting ends on the forward and back travel respectively, substantially as set forth.

6. A valve comprising a case having oppositely-located seats, guides along the inner sides of the case terminating in abutting ends, abutments beyond such ends, with an intervening recess, and a non-rotary central base adjustably mounted on a valve-stem having 50 inclined faces on opposite sides, centrally-mounted rotating valve-disks thereon provided with corresponding inclined faces, and projecting arms adapted to engage such abutments and abutting ends on the forward and 55 back travel respectively, substantially as set forth.

7. In a valve provided with guiding edges terminating in abutting ends, abutments beyond such abutting ends, with an intervening 60 space: rotating disks mounted on a non-rotating base and having lateral arms adapted to engage the abutments and to bear upon the abutting ends, and to reverse the disks upon backward movement, substantially as set 70 forth.

8. In a valve provided with rotating disks having lateral arms with rollers mounted therein and adapted to be seated upon the valve-faces, guiding edges for the lateral arms 75 terminating in abutting ends, substantially as set forth.

In testimony whereof I have hereunto set my hand this 12th day of July, 1897.

ROBERT C. BROMLEY.
